CROSSHEAD SHOE OR THE LIKE

Lawrence Richardson, Melrose, Mass.

Application March 7, 1939, Serial No. 260,423

6 Claims. (Cl. 308—3)

This invention relates to that class of machine elements which in use oppose some mating surface and in consequence of the relative motion resulting from the conditions of use are subject to wear, usually more rapid in the element itself than on the cooperating surface, which in time produces an excessive clearance between the parts which must be eliminated by a replacement or reconditioning of the worn part. An outstanding example of such class is the crosshead of a steam locomotive wherein the movement is a sliding movement of the head along the crosshead guide, and the operating surface of the crosshead, which frequently is formed of some relatively soft, anti-friction metal, wears away relatively rapidly. The object of the invention is to provide an inexpensive and efficient construction for such an element capable of a simple readjustment to compensate for wear.

My invention will be well understood by reference to the following description of an illustrative embodiment thereof taken in connection with the accompanying drawings wherein I have shown by way of example a crosshead shoe embodying the invention. In these drawings:

Fig. 1 is a vertical section through a portion of a locomotive crosshead shoe;

Figs. 2 and 3 are sections on the lines 2—2 and 3—3 of Fig. 1, respectively; and

Fig. 4 is a transverse section illustrating a stage in the process of rehabilitating the shoe.

Referring to the drawings, I there show a crosshead shoe of generally channeled form having the web portion 6 which opposes the crosshead guide and the flanges 8 which embrace the sides thereof. The greater part of the wear on the shoe is on the face thereof opposing the guide. To take this wear I have shown the bottom or web portion of the channel as fitted with wear plates 10, which may, for example, be of bronze, and provide means for securely and rigidly positioning them while permitting their ready readjustment (downwardly in Figs. 1 and 2) to compensate for wear. To receive each plate the web portion of the shoe may be provided with a recess 12. Herein this recess is of generally dovetailed form, being undercut at least at the fore and aft ends, as illustrated in Fig. 1, and the bottom of the recess may be provided with auxiliary undercut recesses 14. The plate 10 may have the ends which oppose the undercut ends of the recess correspondingly relieved by beveling them toward the outer or wearing face of the plate. The plate is of such length that it may be inserted in the recess by a simple buttoning

movement, preferably being positioned with one edge abutting against and overhung by the opposed undercut wall, as illustrated at the extreme right in Fig. 2. Between the bevelled edge at the left and the opposing wall a substantial clearance may thus exist.

Interposed between the bottom of the recess and the wear plate 10 I provide means for positioning the plate as such in any one of a number of positions spaced from the bottom. Conveniently these take the form of small bowed springs 16. It is to be noted that these springs are not relied upon to support the wear plate 10 against the thrust of the connecting rod, but are of adequate strength to support the weight of the plate as such and it may be brought to a desired position of adjustment by pressing it inwardly against the resistance of the springs.

To maintain the plate in the desired position, Babbitt metal 18 or similar readily fusible material which will melt at a temperature sufficiently low as not to be destructive of the springs or harmful to the other parts may be flowed into the recess 12 to fill the same to underlie the plate and to imbed the lower part of it. The metal fills the clearance shown at the left hand of the plate in Fig. 1 and interlocks the plate with the overhanging portion of the recess wall adjacent the same. It interlocks with the relieved or bevelled margins of the plate, with the undercut walls of the recess as a whole, and with the auxiliary recesses 14 herein provided in the base.

We may suppose Fig. 1 to represent the crosshead shoe as prepared initially for use. In use the plates 10 wear away and ultimately will require readjustment. To recondition the shoe it may be positioned with the channel up, as shown in Fig. 4, and a plate 20 secured across the flanges 8. Spacing blocks 22 are interposed between the plate 20 and the wear plates 10, the height of these blocks corresponding to the desired distance between the wearing faces of the wear plates 10 and the extremities of the channeled flanges 8. Thus in Fig. 4 we may suppose that the plate 10 originally extended to a position corresponding to the bottom ends of the blocks 22 and that the clearance illustrated in the figure illustrates the wear which has occurred in use and which it is desired to compensate for by adjustment. The parts being in the position shown in Fig. 4, heat may be applied to melt the fusible filling metal 18, releasing the plate to the springs 16 which automatically elevate it to the desired position determined by the spacers 55

22. Additional babbitt may then be poured in to fill the space within the recess thus created, and when the babbitt sets, the face of the plate is repositioned in the same position that it originally had when new.

5 It will be noted that the smooth surface of the plate worn by use into close-fitting relation to the guide is preserved unaltered and merely readjusted in position. No machining is necessary.

10 To facilitate the application of the Babbitt metal 18 I have herein (Fig. 3) shown the lateral margins of the plates 10 as cut away to form gates 24 into which the metal may be poured.

15 I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

.20 I claim:

25 1. A machine element having a wear plate carried thereby for bearing on a surface of a cooperating element to take the wear incident to relative movement of the parts, the carrying element having an overhanging shoulder adjacent the plate, springs underlying the plate and a body of metal fusible at a temperature sufficiently low not to be destructive of the springs or plates interlocked with the shoulder and embedding the lower portion of the plate to retain it in a position determined by the compression of the springs.

30 35 2. A machine element having a wear plate carried thereby for bearing on a surface of a cooperating element to take the wear incident to relative movement of the parts, springs underlying the plate and a body of metal fusible at a temperature sufficiently low not to be destructive of the springs or plates, embedding the lower portion of the plate and securing it to the carrying element in a position determined by the compression of the springs.

40 45 3. A machine element having a wear plate carried thereby for bearing on a surface of a cooperating element to take the wear incident to relative movement of the parts, said carrying element having a recess in the face thereof opposing the cooperating element, the walls of which recess present overhanging parts, the wearing plate being received in the recess and having projecting portions adjacent the inner side thereof, means adapted to support the plate as such in a plurality of positions relative to the bottom of the recess while maintaining a clearance between the plate and the walls of the re-

cess and metal fusible at a temperature substantially lower than the melting point of the plate filling the recess and embedding the inner portion of the plate, the metal entering beneath the overhanging parts and extending over the projecting parts.

5 10 15 20 25 4. A machine element having a wear plate carried thereby for bearing on a surface of a cooperating element to take the wear incident to relative movement of the parts, said carrying element having an undercut recess in the face thereof opposing the cooperating element, the wearing plate having sides relieved at the outer face thereof, which sides oppose undercut walls of the recess, the plate being of a dimension to be inserted and positioned therein with a clearance of at least one of said sides from the adjacent wall, means adapted to support the plate from the bottom of the recess in a plurality of positions while maintaining a clearance between the plate and the walls of the recess, and metal fusible at a temperature substantially lower than the melting point of the plate filling the recess, embedding the inner portion of the plate and entering the clearance.

25 30 35 40 45 5. A machine element having a wear plate carried thereby having an exposed surface for bearing on a surface of a cooperating element to take the wear incident to relative movement of the parts, means adapted to support the plate as such in a plurality of positions relative to said first element to regulate its clearance from the cooperating element, such means defining a space between said member and the lower portion of the plate, and a body of metal fusible at a temperature substantially lower than the melting point of the plate embedding the lower portion of the plate and securing it to its carrying element independently of support by said positioning member.

40 45 50 55 60 65 6. A machine element having a wear plate carried thereby having an exposed surface for bearing on a surface of a cooperating element to take the wear incident to relative movement of the parts, means adapted to support the plate as such in a plurality of positions relative to said first element to regulate its clearance from the cooperating element, such means defining a space between said member and the lower portion of the plate, the carrying element having an undercut recess and a body of metal fusible at a temperature substantially lower than the melting point of the plate filling said recess and embedding the lower portion of the plate and securing it to its carrying element independently of support by said positioning member.

LAWRENCE RICHARDSON.
